UNITED STATES PATENT OFFICE.

RUDOLPH S. BLOME AND WILLIAM J. SINEK, OF CHICAGO, ILLINOIS, ASSIGNEES TO
RUDOLPH S. BLOME COMPANY, OF CHICAGO, ILLINOIS, A PARTNERSHIP.

PAVEMENT.

1,029,575.

Specification of Letters Patent. Patented June 11, 1912.

Application filed July 13, 1911. Serial No. 638,340.

To all whom it may concern:

Be it known that we, RUDOLPH S. BLOME and WILLIAM J. SINEK, citizens of the United States, residing at Chicago, in the county of Cook and State of Illinois, have invented certain new and useful Improvements in Pavements, of which the following is a specification.

It has been customary and usual heretofore in constructing concrete pavements to lay such pavements in arched or crowned shape of substantial uniform thickness on a correspondingly curved ground foundation. We have discovered, however, that better results are attainable in a pavement of this character if it is laid on a substantially flat or horizontal ground foundation, the curved or crowned contour of the top surface of the pavement being secured by making such pavement thicker at the middle of the roadway and of less thickness at the curbs, the depth of thickness gradually decreasing from the center of the roadway to the edges. Pavements constructed in this manner eliminate from them any substantial tendency to crack longitudinally along the center, because of the increased thickness at such part of the pavement, and further, owing to the fact that the traffic is heavier on the central portion of the pavement as distinguished from the gutter parts, a pavement laid in the manner specified conforms more nearly to the actual working requirements of traffic conditions.

Another feature of our invention resides in the bonding or attachment of a suitable surfacing of relatively small thickness to the main body of the pavement so as to do away with the tendency of such surfacing to slide or travel down the surface of the pavement toward the gutters and also to eliminate the tendency which such thin surfacing exhibits to become separated from the top of the pavement as by flaking, due to the difference in contraction and expansion of the composition constituting the surfacing and the body of the pavement proper.

In order that a full and complete comprehension of this invention may be had by those skilled in the art, we have illustrated in the accompanying drawing forming a part of this specification a desirable embodiment of the invention, and throughout

the various views of this drawing like reference characters apply to the same parts.

In the drawing Figure 1 is a vertical cross-section through a pavement embodying our invention; Fig. 2 is a fragmentary plan of the pavement, a portion of the same having the top surfacing removed to more clearly illustrate the manner of bonding such surfacing to the top of the pavement proper, this diagram showing essentially the minimum diameter of the circular locking recesses; Fig. 3 is an enlarged cross-section on line 3, 3, Fig. 2; Fig. 4 is an enlarged cross-section on line 4, 4, Fig. 2; and Fig. 5 is a similar cross-section on line 5, 5 of Fig. 2.

By reference to this drawing it will be observed that the top of the ground foundation 10 between the combined gutters and curbs 11, 11 is substantially flat and horizontal. The pavement under ordinary circumstances can be laid directly on such flat top of the ground except in the colder climates where the underlying ground or soil is composed of clay or other similar heavy material, and where the effects of the elements must be taken into account. Under such circumstances we provide a drainage or foundation to prevent any detrimental action of the cold weather, so that the frost will not crack or cause an upheaval of the pavement. The pavement proper laid between the curbs and on the ground consists preferably of a lower or underlying stratum 12 desirably composed of one part of Portland cement and eight parts of an aggregate consisting of 50 per cent. of what is known as $1\frac{1}{2}$ inch stone and gravel with all particles below a half inch eliminated, 15 per cent. of $\frac{1}{4}$ inch hard stone or gravel, and 35 per cent. of clean torpedo sand. Such concrete is laid and compacted in the usual manner and on the same is superposed an upper layer 13 composed of one part of Portland cement, one part of coarse torpedo sand, and one part of a mass of hard particles or pieces such as broken stone, gravel, conglomerate, hard slag, or similar hard substance, equal in quantity to the volume of sand. This mass consists desirably of 25 per cent. of $\frac{1}{4}$ inch size, 50 per cent. of $\frac{3}{8}$ inch size, and 25 per cent. of $\frac{1}{2}$ inch size, the ingredients having substantially all finer or smaller particles elimi-

nated, which can be readily accomplished by the well-known method of screening. These combined layers 12 and 13 are thicker at the center of the roadway than at the 5 gutters, in some instances being approximately seven inches thick at the center of the road and gradually decreasing to a thickness of five inches at the curbs.

It has heretofore been attempted to apply 10 to a concrete pavement a thin bituminous or coal-tar product surfacing of various kinds, but this has not met with success because the desired and necessary union or bonding of such thin top surface of the 15 pavement proper has not been secured. To improve such union or bonding constitutes one of the objects of this invention and we accomplish it by passing over the top of the layer 13, after the concrete has become set 20 sufficiently for the purpose in view, a hand roller provided with suitable projections and ribs to form in the surface of the concrete a series of distinct separated recesses or cavities 14 with flat bottoms 15 and directly 25 connected together by grooves 16 and also connected together by the intersecting grooves 17 and 18, all of such grooves being preferably V-shape in cross-section, as shown in Fig. 5. These cavities and grooves are 30 desirably made substantially $\frac{1}{2}$ inch in depth, (although this may be varied, of course, to suit different conditions, and I sometimes prefer to make the cavities somewhat deeper than the grooves and also greater in diameter and of other shapes than as shown in the drawing,) and then the top surfacing of 35 suitable material such as paving pitch, bituminous substance, a coal tar product desirably fluxed with a small amount of coal tar, or asphalt properly fluxed is applied, 40 so that the top of the pavement will have a surfacing substantially $\frac{1}{2}$ inch thick, but such surfacing will have downwardly-extended projections and ribs fitting into the 45 corresponding cavities, recesses, and grooves in the pavement proper, so that a firm and secure anchorage is directly effected for the limited thickness of coating material. In this way the very thin top surfacing is effectively 50 bonded and united with the pavement in such a manner that it cannot become detached or shift in position. This surfacing is desirably of a dark color so that under bright light it will not have a detrimental or objectionable effect on the 55 eyes. Such an anchoring of the surfacing to the concrete pavement is desirable in summer when the top coating becomes more pliable and has a tendency to shift on the 60 pavement, and is also desirable in the winter when this top surfacing becomes more rigid. The fitting of the ribs and projec-

tions in the diagonally-disposed intersecting grooves and recesses respectively binds the surfacing from movement in all directions, 65 and prevents the usual cracking of the top surface due to the strains of expansion and contraction. While this coating is still hot and after the same is in place, it is preferably spread with a thin layer of fine sand 70 and the pavement as a whole is desirably supplied with suitable expansion joints across the street at the required intervals and also along the curb; in those instances where the pavement is provided with such 75 a curb.

While we have herein specified the various amounts and parts of ingredients of the pavement and have set forth in detail the different dimensions and also the shapes and 80 arrangements of the recesses and grooves, it is to be understood that our invention is not limited to these precise and exact details because they can be varied within wide limits without departure from the heart of 85 the invention and without the sacrifice of any material or substantial benefits accruing from the invention.

What we claim is:

1. A pavement including a foundation 90 provided with longitudinal parallel grooves extending throughout the length of the pavement, transverse parallel grooves extending the entire width of the pavement, diagonal parallel grooves extending throughout the width of the pavement and crossing the other grooves at their points of intersection, and cavities at each of the intersections of the several grooves, the walls of such cavities being vertical, and a surfacing on top of the foundation and extending into the grooves and the cavities, substantially as described.

2. A pavement including a foundation provided on its top surface with intersecting V-shaped grooves, and cavities at the intersections of the grooves, the walls of said cavities being substantially vertical, and a surfacing on top of the foundation and extending into the grooves and the cavities, substantially as described.

3. A pavement including a foundation provided with longitudinal, transverse, and diagonal intersecting V-shaped grooves, and cavities at the intersections of the grooves, 115 the walls of such cavities being substantially vertical, and a surfacing on top of the foundation and extending into the grooves and the cavities, substantially as described.
